United States Patent Office

Des. 177,473
Patented Apr. 17, 1956

177,473

HEADBOARD

John T. Kenney, Norfolk, and George S. Broughton, Riverton, Conn., assignors to The Hitchcock Chair
Company, Riverton, Conn., a corporation of Connecticut

Application September 16, 1955, Serial No. 37,955

Term of patent 14 years

(Cl. D5—4)

Fig. 1.

Fig. 2.

Fig. 1 is a front view of a headboard embodying our new design.

Fig. 2 is an end view thereof; the opposite end of said headboard being the same as that illustrated.

I claim:

The ornamental design for a headboard, as shown and described.
